TOBACCO PIPE

Frederick Hudes, Kew Gardens, N. Y.

Application February 23, 1939, Serial No. 257,860

5 Claims. (Cl. 131—176)

The invention relates to tobacco pipes, and has among its objects the provision of an improved removable tilttable cover therefor.

In tobacco pipes having resilient covers to permit springing apart of the arms that receive the bowl therebetween for release of the pivotal fastening means for removal of the cover, there is the ever present danger that the cover may be unduly strained or may be broken when the operator forces the arms apart. This is particularly true if the cover be made of Bakelite or other composition material, which is relatively brittle or has very little elasticity.

Accordingly it is an object of the invention to provide means which shall avoid this difficulty and shall semi-automatically spring the arms apart to an exact predetermined degree.

Another object of the invention is to provide improved mounting means for the cover to reliably hold the same against accidental tilting to open position, even though the cover is otherwise mounted loosely and arranged with clearances for quantity production manufacture.

A further object of the invention is to provide such a cover with an auxiliary horizontal cover.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary view in side elevation of a tobacco pipe embodying the invention, and showing the cover in open position in dot dash lines.

Fig. 2 is a similar view of the pipe with the cover removed.

Fig. 3 is a central sectional view of the bowl and cover in the closed position of the latter.

Fig. 4 is a vertical sectional view of the cover alone.

Fig. 5 is a fragmentary sectional view showing the fastening means in the open position of the cover.

Fig. 6 is a central sectional view of a modification having main and auxiliary covers.

Fig. 7 is a central sectional view of the cover structure alone.

Fig. 8 is a fragmentary view in side elevation

showing a modification of the invention, in respect to the fastening means for the cover.

Fig. 9 is a horizontal sectional view on the line 9—9 of Fig. 8.

Fig. 10 is a view in side elevation of the bowl.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a tobacco pipe embodying the invention. The same may include a pipe bowl 11 having a stem. For the opening of the pipe bowl, there is provided a cover 13 comprising a perforated cover section 14, undercut at its lower face 15, and having a pair of depending spaced integral arms 16. The latter receive therebetween the bowl 11, and are shaped to fit the contour of the bowl, while seated against the flat faces 17 thereof in the closed position of the cover. For tiltably mounting and securing the cover to move from the open dotted line position of Fig. 1 to the closed full line position thereof shown therein, head and socket means are provided as herein-after described, which are releasable by slightly springing apart the arms 16.

In general, the head and socket means is so constructed as to prevent the cover from accidentally tilting from closed to open position, especially as suitable clearance must be allowed for in quantity production work, it being desirable to avoid expensive finishing operations. Further, it is essential that in attaching and removing the cover, the operator shall not be called upon to force the arms apart and thus to mutilate or break the cover arms.

To realize these purposes, the head and socket means referred to may comprise at each arm 16 a plurality of spaced heads 18, 19 and a recess therefor, the latter of which may include individual sockets for the heads. While the heads 18, 19 may be provided on the arms and the sockets on the bowl, I prefer to form the heads in this instance on the bowl, and the corresponding sockets 18a, 19a, on the arms 16.

Desirably the head 18 is eccentric to the cover and bowl, so that the cover may swing to lateral open position about the head 18. The head 19

may be placed anywhere, but both of the heads ought to be disposed near the lower ends of the arms 16 to permit ample flexure of the latter.

It will now be seen that when both heads 18, 19 are in engagement in their respective sockets, accidental tilting of the cover to open position is prevented. On forcibly moving the cover to the open position shown, the head 19 disengages from its socket and rides along the flat face 17 to cause the arms 16 to spring apart for removal of the cover by merely pulling the cover laterally from the bowl. To facilitate the disengagement of the head 19 the same may be suitably tapered or cam shaped in order to slide out of its socket without breakage. It is noted that the head 19 is substantially nearer to the end of the arm 16 because the flexure there is greater than at the head 18, so that the head 19 may release without wholly releasing the head 18 from its socket. And yet a pull on the cover will suffice to fully disengage the thus partially disengaged head 18. Hence the cover may remain pivotally mounted in its open position.

If desired, the head 18 may normally have a slightly greater depth of engagement in its socket 18a than the head 19 has in its socket 19a to effectively realize the purposes hereinabove stated. Since these heads are very small, being in the neighborhood of $\frac{3}{64}$ or $\frac{1}{16}$ in height, for Bakelite, it is not feasible to attempt to accurately show the shape and proportions of the different heads, but the description clearly indicates the principles involved.

According to Figs. 6 and 7, a cover 13a is used, mounted like the cover 13 and being like the latter, except that it is formed in its top portion 20 with an opening 21 which forms a continuation of the pipe bowl cavity and thus adds capacity to the pipe. An auxiliary perforated cover disc 22 pivotally connected to the part 20 at 23 may be horizontally swingable to open and close the opening 21. This provides a desirable variation to people who wish to have that type of cover, and prefer to have added bowl capacity when smoking in windy weather.

In Figs. 8, 9 and 10 is shown a fastening means which is similar in principle to that indicated at 18, 19. Here the cover 13b for the bowl 11a may have a pair of heads 23, 24 at each arm 16a, with both heads extending along a horizontal line. A recess or socket shaped to receive these heads is provided, comprising a groove 24a open at one end and terminating at its other end in a recess 23a, for their corresponding heads 24, 23. The operation is such as to prevent accidental tilting of the cover from closed position by reason of the engagement of the heads 24 in the grooves 24a. Further, the head 24, which is of slightly less height than the head 23, springs the arms 16a apart on tilting the cover to open position, to partially but not wholly, disengage the head 23. On attaching the cover to a bowl, the heads 23, 24 enter and ride in the groove 24a until the heads 23 snap into their recesses 23a, the heads 24 remaining in their grooves to act as stops. On tilting the cover the heads 24 are forced out of the grooves 24a and spring the arms apart for partial release of the heads 23 from their recesses for easy removal of the cover. It is noted that whereas the head 19 is at a different elevation than the head 18 so as not to accidentally snap into the socket 18a, such an occurrence cannot take place with the elements 23, 24 which may accordingly be horizontally arranged.

The provision of the groove 24a results in certain distinct advantages, in that it permits the pivotal heads 23 to be made relatively large and rugged, without necessitating an undue springing apart of the cover arms, and nevertheless permits a large depth of engagement in their recesses 23a in the vertical direction to reliably hold the cover in its closed position. Such substantial engagement occurs also even when the heads 24 spring the cover arms apart in the open position. Moreover, the attachment of the cover to the pipe bowl is simplified since the cover arms are initially sprung apart only by the heads 23 which easily enter the grooves.

It is thus seen that the invention fulfills the objects stated and is inexpensive in manufacture and reliable in use, and permits the cover to be easily removed for cleaning or replacement by a cover of another construction or design.

I claim:

1. A tobacco pipe having a pipe bowl member, a cover member therefor having depending arms receiving the bowl member therebetween, and means at each side of the bowl member interengaging the latter and the adjacent arm, each means including a plurality of heads and recesses therefor, said arms consisting of a relatively resilient material and being adapted to be sprung apart, and the cover member being tiltable and removable, and the cover member cooperating with each of said means so that the heads of each means engage in their respective recess in the closed position of the cover member to prevent accidental tilting of the cover member, and one head of each means being forced out of its recess and serving to spring the arms apart on forcibly tilting the cover member to open position, certain aligned heads constituting the pivots for the tilting of the cover member and having a slightly greater depth of engagement in their recesses than the remaining heads have in the recesses of the latter.

2. A tobacco pipe having a pipe bowl member, a cover member therefor having depending arms receiving the bowl member therebetween, and means at each side of the bowl member interengaging the latter and the adjacent arm, each means including a plurality of heads and recesses therefor, said arms consisting of a relatively resilient material and being adapted to be sprung apart and the cover member being tiltable and removable, and the cover member cooperating with each of said means so that the heads of each means engage in their respective recesses in the closed position of the cover member to prevent accidental tilting of the cover member, and one head of each means being forced out of its recess and serving to spring the arms apart on forcibly tilting the cover member to open position, said recesses comprising guide grooves each open at one end and terminating at its closed end in a depression of greater depth than the groove, the heads pivotally seating in the depressions being of greater height than the other heads and being adapted to enter and slide in the grooves to spring the cover arms apart and to permit the latter to spring together on seating in the depressions, the said other heads being adapted to enter and engage in the grooves for stop coaction therewith in the closed position of the cover and being adapted to be forcibly removed therefrom on tilting the cover to open position to spring said arms apart, as aforesaid.

3. A tobacco pipe having a pipe bowl mem-

- ber, a cover member therefor having depending integral arms receiving the bowl member therebetween, and means at each side of the bowl member interengaging the latter and the adjacent arm, at least one of said means including a pivot head and a stop head and recesses therefor, the pivot head having a greater height than the stop head, said arms consisting of a relatively brittle slightly resilient material of low heat conductivity and being adapted to be sprung apart, and the cover member being tiltable and removable, and the cover member cooperating with each of said means so that the heads of said means engage in their respective recesses in the closed position of the cover member to prevent accidental tilting of the cover member, and the stop head being forced out of its recess and serving to partially spring the arms apart on forcibly tilting the cover member to open position with the pivot heads still engaged in their recesses, to thus facilitate removal of the pivot heads and hence of the cover member in the said open position by exerting a pull on the cover member to cause the pivot heads to complete the springing apart of the arms.
4. A tobacco pipe having a pipe bowl member, a cover member therefor having depending arm members adapted to snugly receive the bowl member therebetween, and means interengaging the arm members with the bowl member for removably mounting the cover and for swinging movement of said cover between open and closed position, said means including a groove in one of the bowl and arm members, said groove terminating in an open end near an edge of its member, said groove terminating in an open end near an edge of its member, said groove terminating at its other end in a depression of greater depth than the groove, the companion member having a head adapted to enter the groove at its open end and to ride along the groove and snap into the depression on applying the cover to the pipe bowl, the cover and its arm members being a one-piece structure consisting of brittle material of low heat conductivity and having a limited yieldability to permit the arm members to be slightly sprung apart, said arms being so sprung apart when said head is in said groove, and said arms being in normal position when the head is in said depression, the latter having its full depth greater than that of the groove substantially at all sides except at said groove.
5. A tobacco pipe having a pipe bowl member, a cover member therefor having depending arm members adapted to snugly receive the bowl member therebetween, and means interengaging the arm members with the bowl member for removably mounting the cover and for swinging movement of said cover between open and closed position, said means including a groove in one of the bowl and arm members, said groove terminating in an open end near an edge of its member, said groove terminating at its other end in a depression of greater depth than the groove, the companion member having a head adapted to enter the groove at its open end and to ride along the groove and snap into the depression on applying the cover to the pipe bowl, the cover and its arm members being a one-piece structure consisting of brittle material of low heat conductivity and having a limited yieldability to permit the arm members to be slightly sprung apart, said arms being so sprung apart when said head is in said groove, and said arms being in normal position when the head is in said depression, the latter having its full depth greater than that of the groove substantially at all sides except at said groove.

FREDERICK HUDES.
